UNITED STATES PATENT OFFICE

139,549

DESIGN FOR A SHIP

Christoffer Hannevig, New York, N. Y.

Application May 19, 1944, Serial No. 113,685

Term of patent 7 years

(Cl. D71—1)

To all whom it may concern:

Be it known that I, Christoffer Hannevig, a subject of the King of Norway, residing at 25 West 54th Street, New York city, county and State of New York, have invented a new, original, and ornamental Design for a Ship, of which the following is a specification, reference being had to the accompanying drawing, forming part thereof, and in which:

I claim:

The ornamental design for a ship, as shown.

CHRISTOFFER HANNEVIG.
